UNITED STATES PATENT OFFICE.

IRVING L. SHELDON, OF FALL RIVER, MASSACHUSETTS.

PAPER-BOX MACHINE.

SPECIFICATION forming part of Letters Patent No. 639,449, dated December 19, 1899.

Application filed June 29, 1898. Serial No. 722,257. (No model.)

To all whom it may concern:

Be it known that I, IRVING L. SHELDON, a citizen of the United States, residing at Fall River, county of Bristol, State of Massachusetts, have invented a new and useful Machine for Making Paper Boxes, of which the following is a specification.

My invention relates to the manufacture of paper boxes; and has for its object to provide an inexpensive machine especially adapted for making oval boxes, which shall be so simple in its construction and mode of operation as to do away with the necessity for a high grade of skilled labor, shall be practically impossible to get out of repair, and which shall be capable of such rapid operation as to greatly reduce the cost of making certain styles of paper boxes.

With these ends in view I have devised the simple and novel machine of which the following description, in connection with the accompanying drawings, is a specification, letters and numbers being used to designate the several parts.

Figure 1 is a plan view of the machine complete; Fig. 2, a section on the line 2 2 in Fig. 1; Fig. 3, an enlarged sectional view on the line 3 3 in Fig. 1; Fig. 4, an enlarged detail view of the cutters for the covering-strip; Fig. 5, an elevation, on an enlarged scale, of one of the heads; and Fig. 6 is a perspective, on a reduced scale, of the box as formed by the first operation—that is, before the covering-strip is applied.

A denotes the framework, which may be of any ordinary or preferred construction; B, a table for the glued blanks C, which form the sides of the boxes; D, a box-bottom; E, covering-paper, a roll of which is ordinarily mounted at the rear end of the framework; F, a glue or paste tank; G, a glue-roller; H and J, respectively, the fixed and the movable cutters, and K heads adapted to turn on an axle L, which is itself transversely attached to a shaft M, journaled in the framework.

The blanks C are notched at their outer edges, leaving tabs 10 between the notches, each blank being glued on the under side at the outer edge and at the rear end. I have indicated the position of the blanks on table B by dotted lines, and have also by a dotted line 11 indicated the limit of the glued strip

at the outer edge and rear end of the strip, the glued strip at the outer edge ending with the base-line of the tabs, so as to prevent glue from getting upon the inner side of the box. The tabs in practice are a half inch, more or less, in length. 12 denotes a gage upon table A, which may be adjusted at any required position on said table to place the base-line 60 of the tabs in line with the outer edge of the contiguous head. I have shown the table as provided with slots 13 and the gage as adjusted by means of rods and thumb-screws, (indicated by 14,) it being, of course, unimportant, so far as my present invention is concerned, in what manner the gage is adjusted. In starting upon a new lot of boxes the operator loosens the thumb-screws and sets the gage, so that when the inner edges of the 70 blanks rest against the gage the base-line of the tabs will be just in line with the outer edge of the head, the tabs extending outward beyond the head.

Two operators are required to run the machine. In starting, the first operator takes a box-bottom D and attaches it to the outer face of the head, contiguous to table B, by means of the points 15, which extend outward from the outer faces of the heads. As it is wholly unimportant, so far as my present invention is concerned, where the table or other receptacle for holding the box-bottoms is placed, I have omitted it from the drawings and have only shown one of the bottoms in 85 Fig. 6. Having fixed a bottom in place on the outer face of the head, the operator takes a blank C and places the outer portion of the forward edge thereof in engagement with a suitable clamp 16, just within a slot 17 in the 90 periphery of the head. The special construction of the heads and the clamps for retaining the forward ends of the blanks is not of the essence of my invention. Any preferred style of head may be used; likewise any style of clamp that will engage and retain the edge of the blank when the latter is passed in between the jaws. In the present instance I have shown a style of clamp in which the movable jaw is fixed to a rod and a lever 18 is provided at the opposite end of the rod to release the hold of the clamp upon the blank after the box has been formed.

As already stated, the heads K turn upon

axle L. Each head is carried by a sleeve 19, which also carries a bevel gear-wheel 20. These bevel gear-wheels are adapted to mesh with bevel-pinions 21, which are keyed to shafts 22, journaled in the framework, but are adapted to slide longitudinally on said shafts, said bevel-pinions being shown as secured to the shafts by a spline and groove connection. The hub of each bevel-pinion is 5 provided with a groove 23, which is engaged by a yoke 24 upon a slide 25, said slides moving in straps 9 and being operated to move the bevel-pinions into and out of engagement with the bevel-gears and cause the heads to 10 rotate by means of bell-crank levers 26, connected by rods 27 to treadles 28, springs 29 acting to hold the slides normally retracted and the bevel-pinions out of engagement with the bevel-gears. In the drawings both bevel- 15 pinions are shown as in engagement with the corresponding bevel-gears, the treadles 28 being represented as pressed down and the heads as being rotated. It should be understood, however, that the operation of each 20 head is wholly independent of the operation of the other head, one head being in practice controlled by one operator who makes the box, the other being controlled by the other operator who puts on the covering-strip, as will be 25 more fully explained. Shafts 22 are continuously in rotation when the machine is in use. In the present instance I have shown these 30 shafts as carrying worm-wheels 50, which engage worms 51 on a shaft 52, journaled in the framework. Shaft 52 receives motion from 35 a belt (not shown) which passes over belt-pulley 53, the belt preferably passing up through the floor, although the machine may be driven from an overhead counter-shaft, if 40 preferred.

30 denotes a stop-plate carried by shaft M, which is provided with projections 31, adapted to be engaged by locking-pawl 32.

33 denotes a spring the action of which is 45 to hold both pawls in engagement with opposite sides of either of the projections.

34 denotes an operating-rod pivoted to one of the pawls and supported by a bracket 35, by means of which the pawl to which it is attached may be drawn out of engagement with the stop-plate, said stop-plate itself acting to carry the other pawl out of the way when rotated in the direction of the arrow in Fig. 3.

Having engaged the forward end of a blank 50 B with the contiguous head by means of clamp 16 the first operator places his foot upon the corresponding treadle 28, moves slide 25, and places one of the bevel-pinions 21 in engagement with the corresponding bevel gear-wheel 55 and imparts rotation to the head. The instant the operator removes his foot from the treadle the corresponding spring 29 will retract the slide 25 and disconnect the bevel-pinion from the gear-wheel, leaving the head 60 without driving power and wholly at the control of the operator by hand. After the head has made a revolution the first operator

presses the overlapping rear end of the blank B, which, as already stated, has been glued upon its under side down to place, which secures the ends of the blank B together and forms the sides of the box. Simultaneously or an instant later the operator may fold tabs 10, which, as already stated, have been glued on the under side over upon the outer side of the bottom D, thereby securing the bottom and sides together, and thus completing the formation of the box proper, as is clearly shown in Fig. 6, it being of course understood that lids may be made the same way as the boxes and that boxes may be made of any height up to the extreme width of the heads, it being simply necessary to change gage 12 each time the height of the boxes is changed, so as to place the base-line of the tabs in line with the outer edge of the head.

It should be understood that the special mode in which the machine is operated is not of the essence of my invention. For example, the folding of the tabs over upon the bottom of the box may, if preferred, be left for the second operator to do while putting on the covering-strip.

As soon as the first operator has completed the box the second operator by means of rod 34 disengages pawls 32 from the stop-plate and gives shaft M a half-rotation, releasing rod 34 the instant the half-rotation of the shaft is completed and locking the parts in position, as before. This half-rotation of shaft M will change axle L end for end and will transpose the heads, so that the box which has been formed upon one head by the first operator will now be in position for the covering-strip to be applied by the second operator, and the head from which the second operator may have just removed a covered box will be in position for the first operator to form another box thereon. The strip of covering-paper, which I have indicated by E, passes over glue-roller G, over and under guide-rollers 36, and between fixed and movable cutters H and J. The movable cutter J is carried by arms 45, which are pivoted to the framework, as at 37, and one of said arms is provided with an extension 38, which extends downward into position to be engaged by a catch 39 upon a lever 40, which is pivoted to a bracket 41, extending from the framework. The other end of lever 40 extends forward into position to be engaged by a pin or lug 42 on the inner face of either of the heads. (See Fig. 1.) A spring 43 acts to draw the rear end of lever 40 upward into operative position, so that catch 39 will engage extension 38, the upward movement of the lever being stopped after the catch has engaged extension 38 by a pin 44. The special features of construction of the cutters are that the blade of the movable cutter J is straight across and the blade of the fixed cutter H is inclined so that a shearing cut is produced, beginning, of course, at the high portion of cutter H and ending at the low portion

thereof. The fixed cutter H is rigidly affixed to a bracket 46, which is itself secured to the framework.

47 denotes a treadle, and 48 a rod which extends upward therefrom and engages one of the arms 45 which carry the movable cutter.

49 denotes a spring the action of which is to draw rod 48 and the movable cutter downward and sever a strip of paper between the

10 cutters with a shearing cut. This operation would of course leave treadle 47 at a raised position. The operator then presses down upon the treadle and raises the cutter to its normal position against the power of spring

15 49. As extension 38 swings to place it engages the outer face of catch 39 on lever 40, swings said lever downward against the power of spring 43 until the arm has passed the catch, when said spring will draw the catch

20 to the locking position and retain it there, as in Fig. 2. The parts will remain in this position until lever 40 is tripped by hand or by the engagement therewith of a pin or lug 42

25 upon one of the heads. This engagement of a lug 42 with lever 40 tilts the forward end of said lever upward and the rear end downward, thereby releasing extension 38 from the catch and permitting spring 49 to actuate the movable cutter and sever the strip of cov-

30 ering-paper, as will be again referred to.

Returning now to the description of the operation in use, as soon as the half-rotation of shaft M is completed the second operator draws the end of the covering-strip forward

35 between the cutters and makes it fast to the box upon the head by rubbing it by hand. The covering-strip provided in practice is an

inch, more or less, wider than the height of the box, half of this extra-width being pro-

40 vided as a finish for the bottom of the box, the other being provided as a finish for the top of the box. As soon as the operator has

45 attached the covering-strip to the box he places his foot upon the contiguous treadle

50 28, moves the corresponding slide 25 and bevel-pinion 21 and communicates motion to the head which he is operating upon. While the head is being rotated the operator rubs the covering-strip by hand and makes it fast

55 to the sides of the box and also folds one edge of the covering-strip over the bottom of the box, covering the tabs by which the bottom is held in place.

If preferred, the folding of the tabs over

55 upon the bottom of the box may be omitted by the first operator, and this operation may be performed by the second operator simultaneously to the putting on of the covering-

60 strip, the second operator using one hand to rub the covering-strip down smoothly upon the sides of the box as the head rotates and the other hand to fold the tabs and with them the edge of the covering-strip over upon the bottom of the box, it being understood, of

65 course, that both the under side of the covering-strip and the under side of the tabs have been thoroughly glued, so as to cause

them to adhere when pressed down to place. The box is now removed from the head and the overlapping edge of the covering-strip at the top of the box is turned over and pressed down by hand on the inner side of the box, which completes the operation. The second operator now releases stop-plate 30 by means of rod 34 and gives another half-rotation to shaft M, which places the head from which he has just removed a box in position for the first operator to form another box thereon, and places the box which has just been formed by the first operator in position to receive the covering-strip. These operations are repeated with great rapidity, completed boxes being formed by the operators in less time than it takes to describe the operation. Half or any portion of the boxes may be covered, if required, by attaching the end of the covering-strip at the necessary place to produce the desired result and allowing the cutters to be operated by pin 42, or the strip may be attached as if the whole box was to be covered and lever 40 tripped by hand, or the position of pin 42 may be changed, a number of threaded holes being provided in the edge of the head to receive the pin, which may be readily moved from one hole to another.

Having thus described my invention, I claim—

1. In a machine of the character described the combination with an axle and heads independently rotatable thereon, of a shaft to which the axle is attached transversely so that a half-rotation of the shaft will transpose the heads.

2. The combination with the axle and the heads, of a shaft by which the axle is carried, mechanism for locking the shaft after the axle has been changed end for end and mechanism for rotating the heads independently on the axle.

3. The combination with the axle and the heads, of a shaft which carries the axle and also a stop-plate 30, pawls engaging the stop-plate by which the shaft is held against rotation and mechanism for rotating the heads independently.

4. The combination with the axle and the heads, of a shaft by which the axle is carried, mechanism for locking the shaft after the heads have been transposed and mechanism for rotating the heads independently.

5. The combination with the axle and the heads, of a shaft to which the axle is attached transversely and which carries a plate 30 having projections 31, pawls adapted to engage the opposite sides of either projection, a spring for holding both pawls in engagement, and an operating-lever for moving one pawl out of engagement so that the shaft may be turned to change ends with the axle.

6. The combination with shaft M and mechanism for holding said shaft against rotation, of an axle attached to said shaft transversely, heads mounted to turn on said axle, bevel gear-wheels 20 which move with the heads,

- sliding bevel-pinions adapted to engage the bevel gear-wheels and means for moving the pinions into and out of engagement independently.
- 5 7. The combination with shaft M and mechanism for holding said shaft against rotation, of an axle attached to said shaft transversely, sleeves mounted to turn on said axle, each sleeve carrying a head K and a bevel gear-wheel, shafts 22 each carrying a sliding bevel-pinion adapted to engage one of the gear-wheels and independent mechanisms for moving the pinions into and out of engagement with the gear-wheels.
- 10 8. The combination with shaft M, the axle secured thereto transversely and heads and bevel gear-wheels mounted to turn on the axle, of shafts 22, bevel-pinions keyed to said shaft and adapted to move longitudinally thereon, slides carrying yokes engaging the bevel-pinions, springs for retaining the pinions out of engagement with the gear-wheels and bell-crank levers and treadles for moving said pinions into engagement independently against the power of the springs.
- 15 9. The combination with shaft M and an axle secured thereto transversely, of heads mounted to turn on said axle and provided with means for engaging the ends of box-blanks and means for retaining box-bottoms.
- 20 10. The combination with shaft M and an axle secured thereto transversely, of heads K mounted upon the axle and provided with means for engaging the ends of box-blanks, means for retaining box-bottoms and mechanism for rotating said heads independently.
- 25 11. The combination with shaft M and an axle secured thereto transversely, of heads K mounted upon the axle and provided with means for engaging the ends of box-blanks, means for retaining box-bottoms, mechanism for rotating the heads independently and mechanism for locking the shaft after a half-rotation to change the axle end for end.
- 30 12. The combination with shaft M and an axle secured thereto transversely, of heads K mounted upon the axle and provided with means for engaging the ends of box-blanks, and means for retaining box-bottoms, and table B having an adjustable gage 12 whereby the heads are adapted to make boxes of any height.
- 35 13. The combination with shaft M, an axle secured thereto transversely and heads K mounted to turn on said axle and provided with pins 42, of fixed and movable cutters, means for retaining the movable cutter out of engagement and intermediate mechanism adapted to be engaged by a pin 42 to release the movable cutter.
- 40 14. The combination with shaft M, an axle secured thereto transversely and heads K mounted to turn on said axle and provided with pins 42, of a fixed cutter having an inclined edge, a movable cutter having a straight edge whereby a shearing cut is obtained, a spring for drawing the movable cutter into engagement, means for retaining the movable cutter out of engagement against the power of the spring and a lever adapted to be engaged by a pin 42 to release the movable cutter and sever a covering-strip.
- 45 15. The combination with shaft M, an axle secured thereto transversely and heads K mounted to turn on said axle and provided with pins 42, of a fixed cutter having an inclined edge, a movable cutter having a straight edge and an arm 38, a lever 40 having a catch adapted to engage arm 38, a spring 43 for holding the arm and catch in engagement, a treadle and rod for raising the upper cutter and a spring 49 for drawing said cutter into engagement so that when lever 40 is engaged by either of the pins 42 said lever will be tilted, arm 38 released and the movable cutter will move into engagement with the fixed cutter.
- 50 16. In testimony whereof I affix my signature in presence of two witnesses.
